UNITED STATES PATENT OFFICE.

WILLIAM E. WADE, OF ROCKLAND, AND THOMAS H. SEELEY, OF MALDEN, MASSACHUSETTS, ASSIGNEES, BY MESNE ASSIGNMENTS, TO UNITED SHOE MACHINERY CORPORATION, OF PATERSON, NEW JERSEY, A CORPORATION OF NEW JERSEY.

FORMING MACHINE.

1,406,307.

Specification of Letters Patent.

Patented Feb. 14, 1922.

Application filed October 13, 1917. Serial No. 196,361.

To all whom it may concern:

Be it known that we, WILLIAM E. WADE and THOMAS H. SEELEY, citizens of the United States, and residents of Rockland, 5 in the county of Plymouth, and Malden, in the county of Middlesex, and State of Massachusetts, respectively, have invented certain Improvements in Forming Machines, of which the following description, in connection with the accompanying drawings, is 10 a specification, like reference characters on the drawings indicating like parts in the several figures.

This invention relates to forming machines and particularly to those adapted to produce a legging from such material as leather.

Heretofore it has been customary to form leggings or puttees by hand, the material 20 being applied to a leg-shaped form and drawn over it by successive pulling and tacking operations by a workman; or the material has been secured to an expandible form, the sections being thereafter separated 25 manually to stretch the material to the desired shape. The hand forming is a step-by-step operation and requires much time of a relatively skillful operator, while the use of an expandible form necessitates the pos- 30 session by the manufacturer of a large number of comparatively expensive devices.

An object of the present invention is to provide a novel machine organized to form leggings, which will have a greater capacity 35 than that of operators working as above described, which will eliminate the many disadvantages characteristic of the formation of leggings as heretofore commonly practised, by the use of which leggings may be 40 formed quickly and satisfactorily without the necessity of employing highly skilled operators, and which will be generally economical in construction and operation.

In one aspect the invention contemplates 45 a novel machine organization for use in making leggings comprising a leg-shaped form, means for engaging the legging material, said means consisting of pairs of members, each pair being arranged to act re- 50 spectively upon the material in the same plane, and means for simultaneously operating the engaging means to move them all together in the same direction to shape the material to the form and hold it under ten-

sion while the material is fastened to the 55 form in its shaped position. The illustrated machine is organized to effect relative manipulations of the leg-form and the engaging means so as to wrap the material about the form and stretch it to cause it to conform in all respects to the shape of said 60 form, the material being clamped by adjacent independently movable members under tension in its shaped condition while it is attached to the form.

Another object of the invention is to provide a machine for forming leggings, which machine, in so far as is consistent with the requirements of good work and of a large range of usefulness, will be power-operated, 70 to the end that each operation of the machine may proceed as rapidly and with as little attention on the part of the operator as is practicable, and important features of the invention reside in the novel organization and operation of the various elements 75 of the machine by which this object is attained in the illustrated embodiment of the invention.

When, as is usual, the leggings are formed 80 from leather manipulated while the leather is in a moist condition, the leggings are commonly left upon the form until they are sufficiently dry to retain their stretched shape and formation. With a view to facilitating this procedure without impairing the capacity of the machine, the leg-form of the illustrated machine is removably mounted in such manner that the form with a legging 85 thereon may be readily taken from the machine and another form substituted therefor.

In accordance with another feature of the invention, the work-engaging members are arranged to occupy an active position in 95 close proximity to the form, as between said form and the operator, or a position at one side thereof to give the operator free access to the form. In the present instance the gripping members are mounted upon a support or carrier swinging about a vertical axis above a horizontally extending form. The clamping members are here shown as mounted on supports at each side of the form movable toward and from the same, 100 the members being independently movable upon each support under the influence of common actuating means. The initial travel

of both the gripping and clamping members may be manual, followed by movement through mechanical operation.

As another feature of the invention the carrier for the gripping members, while movable as a whole, as just described, is in sections independently movable while in the active position, this independent movement causing the gripping members to open to 10 prepare for the introduction of the material. Thereafter the sections may move together to bring the edges of the material between the gripping members, which are closed by a further independent movement of the 15 members. The gripping members are arranged oppositely with tension-equalizing means interposed between them for the purpose of equalizing the tension on the opposite sides of the material. A succeeding 20 travel of the carrier sections, upwardly, exerts tension on the material to draw it about the form, and finally, after the release of the gripping members, the carrier sections are raised together to a point from which 25 they may be swung clear of the form.

Still another feature of the invention concerns the work-engaging means, particularly the clamping members, which come into action after the gripping members to 30 secure the tensioned material against the form in preparation for its final tacking by the operator. These clamping members, like the gripping members, act upon adjacent portions of substantially the entire 35 length of opposite edges of the material and preferably along practically continuous lines. In the present embodiment of the invention the clamping members at each side of the work are upon a support common 40 to all which may be moved manually to effect a rapid travel of the members from a position clear of the form to their operating position. Then power operated means may finally press the clamping members through 45 interposed yieldable connections into the final clamping position. A further feature relates to means for releasing the work-engaging members, such a means being here disclosed applied both to the gripping and 50 clamping members. With the latter the expansion of their yieldable connections furnishes means for moving said members and their supports clear of the work.

An additional feature of the invention 55 concerns means for adapting the machine for operation upon different sizes of work. In accordance with this phase of the invention, the shaping members prior to actual engagement with the work are moved 60 differently for the different sizes, so that they may have a definite relation to said work for all sizes before beginning the shaping operations. As herein described, the extent of approach of the gripping 65 members is variably determined by such

means as a controlling member co-operating with a controlling surface carried by the form support, said support being adjustable to positions dependent upon the size of the leggins being produced. The position to 70 which the clamping member supports are manually moved may also be varied to correspond to the size, this too, being shown as accomplished by the position of the form support which is caused to alter the location of an element of the locking means for the supports.

The foregoing, together with other features, are illustrated in the accompanying drawings, in which— 80

Fig. 1 is a full side elevation of a particular embodiment of the invention;

Fig. 2 is a partial front elevation of the machine;

Fig. 3 is an enlarged side elevation, parts 85 being broken away;

Fig. 4 is a horizontal section on the line 4—4 of Fig. 2;

Figs. 5, 6 and 7 are fragmentary views 90 in front elevation illustrating various positions of the work-engagement elements, and

Fig. 8 is a diagram showing the cycles through which the cam mechanism moves the parts.

Upon the base frame 10 in vertical ways 95 12 is movably mounted a bracket 14 from the upper portion of which there extends horizontally a center 16, preferably conical, like the center of a lathe, and surrounded by a contact surface 17. This center is 100 adapted to enter a corresponding recess in a form 18, which has the shape of the lower portion of a leg from just below the knee to the ankle and which is of such circumference that the largest size of legging may 105 be formed upon it. As illustrated, the center 16 is applied to the recess at the ankle end of the form though it can be oppositely placed if desired. In the other extremity of the form is a like recess to receive a center 20, this center being surrounded by a contact surface 21 and being carried, extending in the direction of the axis of the opposite center 16, upon the upper end of an arm 22 pivoted at 24 upon 110 the bracket 14. Rotatable in a bearing trunnion at 25 in the arm between its pivotal point and the center 20 is a screw 26 held against longitudinal movement by collars 28, 28 upon opposite sides of the arm. 115 At the outer end of the screw is a hand wheel 30 which may be turned by the operator to draw the screw in or out through a nut 32 pivoted upon the bracket. This allows the center 20 to be separated from the center 16 a sufficient distance to enable the operator to introduce the form between them. An opposite rotation of the hand wheel will then bring both centers into engagement with the form recesses so that 120 125 130

the form may be turned freely upon the centers. With the curved or rear side of the form upward the operator may thus attach a sheet S of leather by tacking it at 5 T to the form at its opposite extremities. He then rotates the form and material thereon through 180° bringing the straight side of the form to the top, in which position it may be clamped by further rotation 10 of the hand wheel, which presses the contacting surfaces 17 and 21 firmly against the ends of the form.

From the rear of the base rises an upright 34 on which a vertical rod 36 is mounted between short arms 38, 38 projecting forwardly. About the rod may swing a compound head or carrier having upper and lower sections 40 and 42, respectively, maintained in vertical alinement by a 20 pin 44 rising from the lower section and entering an opening in the upper. The head may be moved about the rod 36 by the operator to a position best shown in Fig. 1 of the drawings to prepare the engaging 25 elements it carries for co-operation with the work, or to either side of this central position entirely clear of the form. In the first-mentioned location the head may be frictionally retained by a spring-pressed stud 45 mounted in the upright 34 and engaging the head section 40. Connected to each carrier section is a downwardly extending portion 46, these two portions sliding over one another between the front face of the 30 upright 34 and a cap plate 48 bolted thereto. At the lower extremities of the extensions are anti-friction rolls 50, the rolls of the sections 40 and 42 resting respectively upon the tops of cams 52 and 54 fast upon a 35 shaft 56 journaled in the base frame. The form of these cams is such that the head sections and members carried thereby will perform a cycle of operations in four successive periods, the character and purpose 40 of which will later appear. Fulcrumed upon opposite sides of the head section 40 on rods 58, 58 are two opposite series of angle levers 60, 60 situated in transversely alined pairs. Each of these levers 60 has three 45 arms, one, 62, extending in a horizontal direction, 64 being an upwardly extending arm, while 66 projects downwardly. Hung upon the extremity of each arm 62 and passing through openings in the lower 50 head section it a work-engaging device 68, this, as illustrated, being of the well-known form disclosed in Patent No. 1,030,264, McFeely, granted June 18, 1912. Each of these work-engaging means includes a casing 55 70 at the lower end of which are work-engaging jaws 72, 72, one of which is pivoted. At the upper end of the casing are oppositely projecting horizontal lugs 74, 74 so related to the lower head section 42 that 60 they may be brought into contact with its upper surface by a movement of the head sections relatively to one another. Within the casing is mounted to move a slide 76 pivoted at 78 to the arm 62 of the lever. At the lower end of the rod a latch 80 is 70 pivoted, projecting through an opening in the casing and having as one of its functions the maintenance of the gripping jaws in their closed relation. The jaws may be released by pressure upon the latch applied 75 outside the casing. The members 68 are arranged in opposite pairs upon corresponding pairs of levers 60, and between upward extensions 82 of the slides 76 of each pair is a helical spring 84 carried by thimbles 86, 86 sliding in a cylindrical opening in the head section 40. These springs exert their expansive force to move the lower ends of the engaging members, and therefore the pairs of gripping jaws, toward one another 80 85 to points above the form 18. Of each pair of levers 60, one has upon its arm 64 a nut 88 pivoted between bifurcations of the arm, while the arm 64 of the opposite lever has a collar 90 similarly pivoted. Through the 90 nut 88 is threaded a rod 92 with its inner end entering the opening in the collar 90. Surrounding each rod between the collar 90 and a collar 96 fast upon the rod is a helical 95 spring 94. These springs, by their expansion, rock both levers of the pairs about their fulcrum points bringing the extremities of the arms 66 into contact with limiting surfaces 97 upon opposite sides of the head section 42. When tension is applied 100 by the gripping members in their operation upon the work, the springs 94 are compressed when the pull becomes sufficiently great, and since either of the levers of a pair can independently compress their common 105 spring the stress upon the work is equalized, the pull being the same on both sides. Outside the nut 88 each rod 92 has fast upon it a hand wheel 98, the hand wheels on adjacent rods being disposed upon opposite 110 sides of machine. The rotation of the rods by these hand wheels compresses the springs 94, and by this means the tension applied to the work before the springs yield may be varied to obtain the proper stretching effect 115 at different points along the edges of the sheet of material. Journaled in the head section 42, extending longitudinally thereof, is a shaft 100 having fixed at opposite extremities arm 102, 102, these arms carrying 120 at their lower ends a bar 104. This bar is in horizontal alinement with the latches 80 of all the gripping members. Upon the outer end of the shaft 100, convenient for manipulation by the operator, is a handle 125 106 through which the bar 104 may be swung in either direction to simultaneously contact with all the latches of a series of the gripping members to trip them and release the jaws. The handle and bar are 130

normally maintained in a central position with the latter element out of engagement with the latches by a spring-pressed stud 108 which may occupy a recess in a vertical 5 surface of the head section 42.

The extent of inward movement of the gripping members toward one another horizontally above the edges of the sheet S of material secured to the form is determined 10 by rods 110, 110, one for each series, these rods running horizontally longitudinally of the head section near the inner faces of the lower extremities of the gripping members. The rods 110 are carried by pairs of arms or 15 controlling members 112, 112 and 114, 114 hung upon the outer and inner ends, respectively, of the fulcrum rods 58, 58. These arms have at their lower ends contact portions 116 variably controlling the position of 20 the rods by engagement with cam surfaces 118, 120 on the arm 22 and bracket 14, respectively, adjacent to the centers 20 and 16. The cam surfaces with which the arms 112 and 114 contact correspond in contour and 25 dimensions with the adjacent portions of the form, and the extent to which the arms move over the surfaces in the descent of the gripping member carrier will depend on the initial vertical relation of the form and gripping members. As here disclosed, the position 30 of the form is altered in accordance with the size of the legging to be formed. Assuming there are to be five sizes, as 14, 14 $\frac{1}{2}$, 15, 15 $\frac{1}{2}$ and 16, the lower portion of the 35 bracket 14 rests upon a cam 122 fixed upon a transverse shaft 124 journaled in the base frame. Upon one extremity of the shaft 124 is a hand wheel 126 through which the operator may rotate it and an index wheel 128 bearing upon its periphery the size numbers 40 previously mentioned. With this index wheel co-operates an index finger 130 secured to the frame. The cam is formed in five successive steps of increasing diameter, 45 the radial distance of these steps from the axis of the shaft being such that when a particular cam surface is brought into contact with the bracket by the rotation of the hand wheel the form will be raised or lowered to 50 a position at which the upper edges of the sheet of material fixed to the form will be in the proper relation to the material-engaging members. Generally the purpose of 55 this adjustment is to keep the upper edges of the sheet in the same horizontal plane. To retain the form-supporting elements against upward movement upon the ways 12 under the tension applied to the material upon the form, the cam 122 has rotating 60 with it a cam 132 having a contour similar to the cam 122 but with the steps oppositely placed. With the periphery of this cam 132 contacts the angular end of a member 134 pivoted at 136 on the lower portion of the 65 bracket 14. As the cam 122 is turned to

raise the form the cam 132 maintains a surface always in contact with the portion 134 so that in all positions of the form a positive stop against upward movement is provided. The rods 110 shifted by the contact 70 of the arms 112 and 114 with the cam surfaces 118 and 120 will position the jaws of the grippers in lines not only corresponding to the upper edges of the sheet of material of the particular size being operated on, but 75 also in accordance with the general inclination of the edges of the sheet as it is applied to the form. This is because the different diameters of the cam surfaces 118, 120 will produce a convergence of the rods 110 toward the rear in accordance with the decrease in diameter of the form. Consequently when the material is brought into 80 proximity with the jaws by the movement of the head it may readily be introduced between them by the operator. The arms 112, 114 are held to the positions to which they are expanded by the cam surfaces by means of latch bars 135 and 136 pivoted respectively upon one of the arms of each pair. 85 These latches are toothed at their free ends and are drawn by springs 138 extending between them and the arms into engagement with detents 140 fixed to the opposite arm of each pair from that upon which the latch 90 bar is pivoted. To release the controlling arms at the completion of an operation by a relative movement between the head sections under the influence of the cams 52 and 54, the latch bar 135 has a screw 142 threaded 95 through it so that when the head section 42 recedes from the section 40 the upper end of the screw comes into contact with the hub of the handle 106. By this the latch bar is pressed down until its teeth are separated 100 from the detent 140, whereupon the gripping members 68 assume their normal inward positions under the influence of the springs 84. The inner latch bar 136 is released by its contact with a screw 144 105 threaded through the head section 42.

In the base 10 at each side of the form in ways 146 is mounted a sliding block or support 148 for a series of clamping members 150. These clamping members consist of 110 slides lying in channels formed in the upper surfaces of the supports, which channels are closed by cap plates 152. At the inner or work-engaging extremities of the slides are removable plates 154 for contact with the material upon the form, these preferably being of some such metal as brass which does not discolor leather by its contact and having their ends shaped to conform to the leg form. The work-engaging edges of the 115 members 150 occupy a practically continuous line to enable them to clamp the material against the form at every point in a horizontal direction. The clamping member supports 148 may be moved manually by the 120

operator in the ways from an outer position clear of the work to a position adjacent to the material upon the form. Each support may be retained in its inner position by a latch 156 pivoted upon the block 148 and provided at its under side with a depression. A spring 157 connects the latch and block to draw the latch depression into engagement with an upward projection 158 upon a retaining member 160 mounted to slide in a channel in the base beneath the block. To the member 160 at the end opposite the projection 158 is pivotally connected a bell crank lever 162 fulcrumed upon the base.

15 The horizontal arm 163 of this lever has a rounded end entering a horizontal slot 165 in the bracket 14. The parts are so proportioned, that as the hand wheel 126 is turned to raise and lower the form for different sizes of leggins the levers 162 move the retaining members 160 so that the projections 158, and therefore the clamping members 150 locked by them, will be located at the same distance from the curved surface 20 of the form for all sizes. This permits the power-operated means now to be described to act on the clamping members through a constant distance.

25 After the preliminary manual positioning, in which the blocks 148 can be slid in through a considerable distance more rapidly than it is feasible by any mechanical means suitable to employ, the machine operates to more slowly force the slides 150 toward the form 30 to clamp the material against said form as it has been stretched by the gripping members. Outside each clamping slide in the channel by which it is guided is an actuating slide or plunger 164, each pair of slides being separated by a helical spring 167.

35 Outward movement of the slides in the channel is limited by bolts 168 securing the cap plates to the blocks, these bolts being surrounded by spacing sleeves 169 which are 40 of such length that the cap plates do not bring pressure upon the slides. The sleeves 169 contact with the ends of the cut-away portions of the slides in which the springs 167 are situated. This arrangement allows 45 the pairs of slides to be normally held at extreme outward positions determined by the bolts and sleeves under the expansive force of the springs 167 and the clamping slide to be forced against the material on 50 the form when pressure is applied to the plungers 164 with a force determined by the character of the springs. In each of the blocks 148, just outside and in alignment with the ends of each series of plungers 164, 55 is journaled a cam shaft 170 having a flat portion 172, which, when presented to the ends of the plungers, will allow them to occupy their normal positions, and a curved or cylindrical portion 174, which will 60 contact with the plungers to force the clamping 65 members toward the form.

Fast upon each of these shafts 174 at the inner end is a bevel gear 178 meshing with a bevel gear 179 splined upon a shaft 180 so that it may move longitudinally thereon while being 70 compelled to rotate. Between the gears 179, the shaft 180 has secured to it a crank arm 182 which is caused to oscillate the shaft 180 through a connecting rod 184 articulated to the upper extremity of a lever 186 pivoted at 75 187 on the frame. The lower end of the lever carries a yoke 188, the arms of which are provided with rolls 190 contacting with opposite peripheral points of a cam 194 fast upon the shaft 56. To release the clamping 80 members 150 from their engagement with the work at the end of the operation, there contacts with the under side of each latch 156 a rod 196 mounted to slide vertically in the base and being carried upon the extremity of a lever system 198, said lever system including a treadle 200 pivoted at the front of the machine. When the operator depresses the treadle the rods 196 are simultaneously raised, lifting the latches 156 from 85 engagement with the retaining projections 158. When the blocks 148 are thus freed, the springs 167 of the entire series of clamping members, compressed by the engagement of said members with the work, expand and cause the retraction of the blocks, which slide in their ways to their outer positions.

90 Power is applied to the actuating shaft 56 by a gear 202 secured thereon and meshing with a pinion 204 carried by one member of a clutch 208 upon a shaft 206 journaled in the base. This clutch may be of the well-known jaw and wedge-actuated type, the movement of the wedge to produce an engagement of the clutch sections and the driving of the shaft 56 being controlled by a treadle 210 adjacent to the release treadle 200 through a connecting lever system 212.

95 Rolls 214, here shown as four in number, are 100 equally spaced about one face of the gear 202 and act upon the lever system to automatically disengage the clutch sections and stop the rotation of the shaft 56, regardless of the position of the treadle 210, after a rotation of the shaft 206 through 90°. Under the influence of this driving mechanism the machine operates in a cycle made up of four periods. Referring to the cam diagram of Fig. 8, at the beginning of the first period, indicated by the numeral 1 on the diagram, the work-engaging elements of the machine 105 occupy the positions illustrated in Fig. 5 of the drawings, the head sections 40 and 42 being raised and separated, so that the gripping jaws are closed, and the clamping members being at their extreme outer limit of 110 rotation with the springs 167 not released, the curved portion of the shaft 170 still being against the plungers. As the rolls of 115

120 the 125 130

- the section extensions 46 ride over the cam surfaces *a* and *b*, as a result of the rotation of the cams 52 and 54 following the first depression of the treadle 210 by the operator, 5 the head section 40 first moves down while the section 42 remains stationary, the contact of the lugs 74 upon the casings of the gripping members with the upper surface of the head 42 causing the jaws to separate. 10 Thereafter, during the later portion of the first period, the head sections move together, until at the end of the first period they are in proximity to the form. During this time the cam 194 moves its surfaces *c* and *i* over 15 the rolls of the lever 186, rotating the cam shafts 170 to free the springs 167. This is preliminary to a later operation of the shaft. At the points indicated by the numeral 2 the cams are all automatically stopped with 20 the parts they actuate appearing as in Figs. 1 to 4. A second depression of the treadle 210 by the operator results in the surfaces *d* and *e* of the cams 52 and 54, respectively, moving the head section 40 upward while 25 section 42 remains fixed until the lugs 74 are separated from the head surface so that the jaws may be closed upon the edges of the material on the form. This is followed by an upward movement of the head sections 30 together to tension the material on the form. The cam 194 during this period, by its surfaces *f* and *g*, causes a dwell of the elements which it actuates. The relation of the elements is shown by Fig. 6. Upon the third 35 depression of the treadle 210 the cams rotate from the point 3. During this time the surfaces *h* and *j* of the cams 52 and 54 are such that the gripping members remain inactive. The surfaces *i* and *c* of the cam 194 rotate 40 the shafts 170 so that the clamping members are forced into engagement with the material and the latter against the form (Fig. 7). The fourth treadle depression leads to a retention of the clamping members 45 in their work-engaging positions under the influence of the surfaces *g* and *f* on the cam 194 while the head sections 40 and 42 are raised to their normal position by the surfaces *k* and *l* of the cams 52 and 54. 50 Considering the general operation of the machine, the form 18 having been placed between its centers with the head 40—42 turned to one side, the operator, by means of the hand wheel 126 and index members 128 and 130, positions the form for the particular size of legging to be operated upon. Then with the curved side of the form uppermost, he bends a sheet of leather over said form and at its opposite edges tacks the 55 sheet to the extremities of the form as indicated at T in Fig. 6 of the drawings. Thereupon, he rotates the form until the tacked side is underneath and locks the form in this 60 position through the pressure of the contact surfaces 17 and 21. Moving the gripping 65 head to its central position and holding the free edges of the sheet vertically, the operator depresses the treadle 210 for the first time. The elements, as far as mechanical actuation is concerned, then assume the positions illustrated in Figs. 1 to 4 of the drawings and as just described in connection with the statement of the cam-controlled cycle. The gripping jaws now being open and adjacent to the edges of the work the 70 operator inserts the sheet between them and again forces down the treadle. This causes the jaws to close and draw up the material into its stretched position (Fig. 6). Following this, the operator simultaneously 75 slides in the opposite blocks 148, as shown in Figs. 2 and 4, which are locked by the engagement of the members 156 and 158. This is preparatory to a third depression of the treadle 210, which causes the rotation of the shafts 170 to yieldingly press in the clamping members 150. By this movement the gripping members are drawn over the form as the edges of the material move in advance of the clamping members. The sheet now being held against the form by these members 150, the gripping jaws are released by the operator oscillating the bar 104 against the opposite latches 80, and the fourth treadle depression causes the gripping members to be lifted to their uppermost 80 position from which they may be swung to one side clear of the work. The operator now tacks the clamped edges at appropriate points, as indicated at *t*, and by pressing down treadle 200 brings the rods 196 against the latches 156, so that the blocks 148 are released and thrown back by the expansion of the springs 167. Rotation of the hand wheel 30 will now free the form from its centers, so that it may be lifted from the machine and the work left upon it to dry. The machine is now ready for the insertion of another form and the operation upon the material secured thereto. 85
- Having thus described our invention, what we claim as new and desire to secure by Letters Patent of the United States is:
1. A machine constructed and organized for use in making leggings and having, in combination, a leg-shaped form, means for engaging legging material, said means consisting of pairs of members arranged along opposite sides of the leg-shaped form throughout substantially its entire length, 115 each pair being arranged to act upon the material on opposite sides of the form, and a single device for simultaneously operating the engaging means to move them all together in the same direction to shape the 120 material to the form.
  2. A machine constructed and organized for use in making leggings and having, in combination, a leg-shaped form, means for engaging legging material, and a movable 130

support upon which the engaging means are mounted to move together for operating said engaging means to stretch the material across the form and hold it at opposite points under equal tension in its form-shaped position for temporary attachment of the material to the form.

3. A machine constructed and organized for use in making leggings and having, in combination, a leg-shaped form to which the legging material may be applied, and means cooperating with the form to shape and hold the material thereto, said shaping and holding means both consisting of series of members movable with respect to the form.

4. A machine constructed and organized for use in making leggings and having, in combination, a leg-shaped form to which the legging material may be applied, means for engaging the legging material, said means comprising a plurality of pairs of opposite members movable towards and from the form, and yieldable connections between the opposite members of each pair acting to equalize the tension on opposite sides of the legging material.

5. A machine constructed and organized for use in making leggings and having, in combination, a leg-shaped form, forming means comprising a plurality of pairs of oppositely arranged and connected members for engagement with opposite edges of legging material in the same plane throughout substantially the entire length of and upon closely adjacent portions of said material, and a single device constructed and arranged to carry all the engaging members and move them simultaneously.

40 6. A machine constructed and organized for use in making leggings and having, in combination, a leg-shaped form, means for engaging legging material, yieldable automatically operating mechanism for relatively moving the form and the engaging means to effect the engagement of the material and its wrapping under tension around and into conformity with the contour of the form, and means to ensure equal tension upon the material at opposite sides of the form.

55 7. A machine constructed and organized for use in making leggings and having, in combination, a leg-form mounted to turn about its longitudinal axis, means acting at both ends of the form to fix it in position, means common to both fixing means to render them effective, means adapted to grip an edge of a sheet of legging material, and means for relatively operating the form and the engaging means to shape the material to the contour of the leg-form.

60 8. A machine for shaping leggings comprising a leg-shaped form, material-engaging means, means for effecting relative movement of the form and the engaging

means to shape the material to the form, means to hold the material in its shaped position for attachment of the material to the form, and power-operated means for actuating the shaping and holding means.

70 9. In a machine for forming leggings, a leg-shaped form, means for engagement with opposite portions of the legging material throughout substantially the entire length of opposite edges to force it about the form, a support upon which all the engaging means are mounted to move together away from the form, and equalizing connections comprising springs interposed between opposite engaging means.

75 10. In a machine for forming leggings, a leg-shaped form, a movable support, and opposite engaging means connected together in pairs and mounted upon the movable support for engagement with successive portions of legging material substantially uniformly spaced between the extremities and throughout the length of opposite edges to force it about the form.

80 11. In a machine for forming leggings, a leg-shaped form, independently yieldable means for engagement with opposite edges of the legging material and all movable together in the same direction to force it about the form, said opposite engaging means being yieldably connected to ensure equal tension at opposite edges of the material.

85 12. In a machine for forming leggings, a leg-shaped form, means for grasping the legging material at successive points throughout the length of opposite edges to draw it about the form, and adjacent independently movable means thereafter acting to clamp the material against the form.

90 13. In a machine for forming leggings from a sheet of material, a leg-shaped form, means for grasping the material at successive points throughout the length of opposite edges to draw it about the form, and means thereafter acting to clamp the material against the form, said clamping means being in series acting upon successive portions of the entire opposite edges of the material.

95 115 14. In a machine for forming leggings from a sheet of material, a leg-shaped form, and means for separate engagement with successive portions of material along a practically continuous line and being independently movable toward the material to force it against the form.

120 15. In a machine for forming leggings, a leg-shaped form, shaping members co-operating with the form, means for moving the shaping members and form relatively to one another, and means operating automatically after the initiation of movement for controlling said movement.

130 16. In a machine for forming leggings, a

- leg-shaped form, shaping members co-operating with the form, means for moving the shaping members and form relatively to one another and means operating automatically 5 in the movement for controlling the shaping members.
17. In a machine for forming leggings, a leg-shaped form, shaping members co-operating with the form, power operated means 10 for moving the shaping members and form relatively to one another, and means operating automatically in the movement for controlling the shaping members.
18. In a machine for forming leggings, a leg-shaped form, gripping members for engagement with the legging material, and power-operated means for moving the gripping members into and out of position for co-operation with the material.
19. In a machine for forming leggings, a leg-shaped form, gripping members for engagement with the legging material, power-operated means for moving the gripping members into and out of position for co-operation with the material, and means controlled in the movement of the gripping members for opening and closing them.
20. In a machine for forming leggings, a leg-shaped form, a plurality of work-engaging means for performing different operations on the work, and power-operated means for actuating the work-engaging means.
21. In a machine for forming leggings, a leg-shaped form, gripping members for engagement with the legging material, clamping members thereafter engaging said material, and independent power-operated means for successively actuating the gripping and clamping members.
22. In a stretching machine, movable members for engaging the material to be stretched, operating mechanism constructed and arranged to move said engaging members through a cycle of operations, and automatic means for stopping the operating mechanism at a predetermined intermediate point in the cycle.
23. In a stretching machine, movable members for engaging the material to be stretched, operating mechanism constructed and arranged to move said engaging members through a cycle of operations, and automatic means for stopping the operating mechanism at a plurality of predetermined points in the cycle.
24. In a stretching machine, movable members for engaging the material to be stretched, operating mechanism constructed and arranged to move said engaging members through a cycle of operations, and automatic means controlled in the movement of the operating mechanism for stopping the operating mechanism at a predetermined intermediate point in the cycle.
25. In a stretching machine, movable members for engagement with the material to be stretched, operating mechanism for successively moving the engaging members, and automatic means for stopping the operating mechanism after the movement of a portion of the engaging members has been effected. 70
26. In a stretching machine, movable members for engagement with the material to be stretched, operating mechanism for successively moving the engaging members, means for stopping the operating mechanism after the movement of an engaging member has been effected, and actuating connections between the operating mechanism and stopping means. 75
27. In a stretching machine, movable members for engagement with the material to be stretched, operating mechanism for the engaging members, driving mechanism for the operating mechanism, operator-controlled means for connecting the driving mechanism and operating mechanism, and automatic means for disconnecting the driving mechanism and operating mechanism after movement of a portion of the engaging members has been effected. 80
28. In a stretching machine, movable members for engagement with the material to be stretched, operating mechanism for the engaging members, driving mechanism for the operating mechanism, operator-controlled means for connecting the driving mechanism and operating mechanism, and automatic means for disconnecting the driving mechanism and operating mechanism after movement of an engaging member has been effected. 85
29. In a forming machine, a leg-shaped form, a carrier movable to occupy either an operating position or a position leaving the form free for access by the operator, and work-engaging members mounted upon the carrier. 90
30. In a forming machine, a form, a carrier movable to occupy either an operating position or a position leaving the form free for access by the operator, work-engaging devices mounted upon the carrier, and power-operated means for moving the engaging devices toward and from the work. 95
31. In a forming machine, a form, a carrier movable to a plurality of positions, work-engaging devices mounted upon the carrier, said devices being normally out of engagement with the work, and means effective in the movement of the carrier for controlling the engagement of the devices with the work. 100
32. In a forming machine, a form to receive material, a standard, a carrier mounted to turn about the standard to positions opposite and clear of the form, material-engaging members controlled by the carrier, 105
- 110
- 115
- 120
- 125
- 130

and means for moving the carrier along the standard to bring the engaging members into and out of co-operation with the material.

5 33. In a forming machine, a form to receive material, a standard, a plurality of carrier sections movably mounted upon the standard, material-engaging members controlled by the carrier sections, and means 10 for moving the sections independently and together in the direction of the form to control the material-engaging members.

15 34. In a forming machine, a leg-shaped form to receive material, material-engaging members situated at opposite sides of the form, means for mounting said engaging members for rapid movement with respect to the form, and means for moving the engaging members more slowly with respect 20 to the form.

25 35. In a forming machine, a leg-shaped form to receive material, material-engaging members situated at opposite sides of the form, means for mounting said engaging members for rapid movement manually with respect to the form, and power-operated means for moving the engaging members more slowly with respect to the form.

30 36. In a forming machine, a leg-shaped form to receive material, material-engaging members situated at opposite sides of the form, means for mounting the engaging members at each side of the form to move together manually, and power-operated 35 means for moving the engaging members with respect to said form.

37. In a forming machine, a leg-shaped form to receive material, material-engaging members situated at opposite sides of the 40 form, means for mounting the engaging members at each side of the form to move together manually, and power-operated means acting simultaneously upon the engaging members at both sides of the form 45 to move them with respect to said form.

38. In a forming machine, a form to receive material, a support mounted for manual movement toward and from the form, a plurality of work-engaging members movable upon the support, and power-operated 50 means common to the engaging members for moving them into co-operation with the material.

39. In a forming machine, a form to receive material, a support mounted at each side of the form for manual movement toward and from said form, a plurality of material-engaging members movable upon each support, means common to the engaging members at each side of the form to move them into co-operation with the material, and power-operated means common to the moving means for actuating them together.

40. In a forming machine, a form to re-

ceive material, a plurality of carrier sections, and a gripping device for the material having members co-operating with separate sections, said sections being movable relatively to one another to operate the 70 gripping device and movable together to control the relation of the gripping device and material.

41. In a forming machine, a form to receive material, a plurality of carrier sections, 75 and a gripping device for the material having members co-operating with separate sections, said sections being separately movable to operate the gripping device and movable together to control the relation of the gripping 80 device and material, and again movable separately to oppositely operate the gripping device.

42. In a forming machine, a form to receive material, a plurality of carrier sections, 85 and a gripping device for the material having members co-operating with separate sections, said sections being movable separately to operate the gripping device, movable together to prepare the gripping device for co-operation with the material, again movable separately to oppositely operate the gripping device and thereafter movable to force the material about the form.

43. In a forming machine, a form to receive material, a plurality of carrier sections, and a gripping device for the material having members co-operating with separate sections, said sections being movable separately to operate the gripping device, movable together to prepare the gripping device for co-operation with the material, again movable separately to oppositely operate the gripping device, thereafter movable to force the material about the form, and finally movable to separate the gripping device and the form.

44. In a forming machine, a form to receive material, a plurality of carrier sections, and a gripping device for the material having members co-operating with separate sections, said sections being movable relatively to one another to open the gripping device to prepare it to grasp the material and movable together to bring the device into grasping position.

45. In a forming machine, a form to receive material, a gripping device having jaws, two carrier sections for the gripping device situated at different distances from the form, means for moving the outer carrier section to open the jaws of the gripping device, and means for moving the sections together to bring the jaws into proximity to the form.

46. In a forming machine, a form to receive material, a gripping device having jaws, two carrier sections for the gripping device situated at different distances from the form, means for moving the outer car-

- rier section to open and close the jaws of the gripping device, and means for moving the sections together to move the jaws into or out of proximity to the form.
- 5 47. In a machine for forming leggings, a leg-shaped form, a support mounted to move laterally to the axis of the form, and a plurality of independently movable members carried by the support and arranged to 70 press the work between them and the form.
- 10 48. In a machine for forming leggings, a leg-shaped form, a support mounted to move laterally to the axis of the form, a plurality of independently movable work-engaging members carried by the support, and yieldable means for forcing each member toward the work.
- 15 49. In a machine for forming leggings, a leg-shaped form, a support mounted to move laterally to the axis of the form at each side thereof, and a plurality of independently movable members carried by each support and arranged to press the work between them and the form.
- 20 50. In a legging-forming machine, a leg-shaped form, a support mounted to move toward and from the form, a plurality of work-engaging members movable upon the support, and means common to all of said 80 members for moving them.
- 25 51. In a legging-forming machine, a leg-shaped form for the work, a support mounted to move toward and from the work, a plurality of clamping members independently movable upon the support, and means common to the clamping members for forcing them into co-operation with the form.
- 30 52. In a legging-forming machine, a leg-shaped form for the work, a support mounted to move toward and from the work, a plurality of clamping members independently movable upon the support, means common to the clamping members for forcing them into co-operation with the form, and 85 yieldable members interposed between each clamping member and the moving means.
- 35 53. In a forming machine, a form for the work, a support mounted to move toward and from the work, a plurality of clamping members independently movable upon the support, a cam shaft for operating the clamping members, and springs interposed between the cam shaft and clamping members.
- 40 54. In a forming machine, a frame, a form carried thereby, a carrier movable toward and from the form, work-engaging members movable upon the carrier, a driving shaft rotatable upon the frame, a shaft rotatable upon the carrier and having means for moving the engaging members, and a connection between the shafts permitting the movement of the carrier.
- 45 55. In a legging-forming machine, a leg-shaped form, a support mounted to move to- 75 ward and from the form, a plurality of work-engaging members movable upon the support, means for securing the support in its forward position, and means whereby the securing means may be released.
- 50 56. In a forming machine, a form, a support mounted to move toward and from the form, a plurality of work-engaging members mounted upon the support, a spring tensioned in the movement of the work-engaging members, means for securing the support against the force of the spring, and operator-controlled means whereby the securing means may be released.
- 55 57. In a forming machine, a form, a support mounted to move toward and from the form, a plurality of work-engaging members movable upon the support, springs tensioned in the movement of the work-engaging members, means for securing the support against the force of the springs, and operator-controlled means whereby the securing means may be released.
- 60 58. In a forming machine, a form to receive material, a plurality of material-engaging members, means common to the engaging members for causing their engagement with the material, and common means to release the members from engagement with the material, such releasing means being independent of the previously-mentioned common means.
- 65 59. In a forming machine, a form to receive material, a plurality of material-engaging members, power-operated means common to the engaging members for causing their co-operation with the material, and common operator-controlled means to release the members from engagement with the material, such releasing means being independent of the previously-mentioned common means.
- 70 60. In a legging-forming machine, a leg-shaped form to receive material, an engaging member movable into co-operation with the material, a retaining device for the engaging member, and operator-controlled means to release the retaining device.
- 75 61. In a forming machine, a form to receive material, opposite series of material-engaging members, releasing means for each series of engaging members, and means common to both series and arranged for co-operation separately with either for causing the release of all the engaging members.
- 80 62. In a forming machine, a form to receive material, movable members for gripping the material, means operable in the movement of the members for causing them to grasp the material, and operator-controlled means for releasing the gripping members.
- 85 63. In a legging-forming machine, a leg-shaped form to receive material, a series of members for gripping the material, means 120
- 90 125
- 95 130

- for causing the members to grip the material, and means common to the series of members whereby they may be released.
64. In a legging-forming machine, a leg-shaped form to receive material, a series of members for gripping the material, means for causing the members to grip the material, a latch for each of the gripping members, and a device arranged to contact with all the latches of the series to effect their release.
65. In a legging-forming machine, a leg-shaped form to receive material, opposite series of members for gripping the material, means for causing the members to grip the material, and releasing means arranged for co-operation with either series of members.
66. In a legging-forming machine, a leg-shaped form to receive material, means for engaging the material, a stop for holding the engaging means in co-operation with the form, and means whereby the stop may be withdrawn to release the engaging means.
67. In a forming machine, a form to receive material, engaging means for the material, a spring arranged to press said means into engagement with the material, a retaining device for holding the engaging means against the material, and means arranged to release the engaging means from the retaining device to permit said engaging means to be withdrawn from the material under the influence of the spring.
68. In a forming machine, a form to receive material, means movable toward the form to press the material against it, a latch for holding the engaging means in co-operation with the form, means whereby the latch may be caused to release the engaging means, and a spring tensioned in the operating position of the engaging means, said spring acting upon the release of the engaging means to separate said engaging means from the material.
69. In a forming machine, a form to receive material, a series of material-clamping members, a spring for pressing each member against the material, a latch for holding the series of members in engagement with the material with the springs compressed, and means arranged to operate the latch to release the engaging members and permit them to separate from the material under the influence of the springs.
70. In a forming machine, a form for use with different sizes of work, work-engaging means co-operating with the form, the form and work-engaging means being relatively movable to stretch the work over the form, and means for variably determining the extent of movement to adapt the form for use with different sizes of work.
71. In a forming machine, a form for use with different sizes of work, and work-engaging means co-operating with the form, said form and work-engaging means being relatively movable to adapt the form for use with different sizes of work, and work-engaging means co-operating with the form, the form and work-engaging means being relatively movable to stretch the work over the form, and means for variably determining the extent of movement to adapt the form for use with different sizes of work.
72. In a forming machine, a form for use with different sizes of work, work-engaging means co-operating with the form, the form and work-engaging means being relatively movable, and means controlled in the movement for variably determining the extent of movement to adapt the form for use with different sizes of work.
73. In a forming machine, a form for use with different sizes of work, and work-engaging means co-operating with the form, said form and work-engaging means being relatively movable, and means controlled during a portion of the movement to adapt the form for different sizes of work.
74. In a forming machine, a form for use with different sizes of work, a plurality of work-engaging members movable into successive co-operation with the form, means for variably determining the extent of movement of the work-engaging members to adapt the form for use with different sizes of work, and means common to the work-engaging members for controlling the determining means.
75. In a stretching machine, means for engaging the material to be stretched upon opposite sides, intermediate material-engaging means, power-operated means for relatively moving the engaging means toward the stretching position, and means constructed and arranged to permit the material and intermediate means to be brought into initial engagement in preparation for the stretching action.
76. In a stretching machine, means for engaging the material to be stretched upon opposite sides, intermediate material-engaging means, power-operated means for relatively moving the engaging means toward the stretching position, and manually operated means constructed and arranged to effect a further movement toward the stretching position.
77. In a stretching machine, a form, means for engaging the material to be stretched at opposite sides of the form, power-operated means for effecting the material engagement, and manually operated means constructed and arranged to move the form toward the stretching position.
78. In a stretching machine, the combination with material engaging means, of a form over which the material is to be stretched, a support for the form, and manually operated means constructed and arranged to move the form and its support with reference to the material engaging means.
79. In a stretching machine, material-engaging members, a form, a form support,

- and a cam engaging the form support to move the form with reference to the material engaging members.
80. In a stretching machine, work engaging members relatively movable toward and from one another, power operated means for effecting the movement, manually operated means for effecting said movement, and means for locking a member in the position 10 to which it is moved manually.
81. In a forming machine, a movable form for use with different sizes of work, work-engaging means movable into co-operation with the form, and means controlled by the 15 movement of one of these elements for varying the movement of the other.
82. In a forming machine, a movable form for use with different sizes of work, work-engaging means movable into co-operation 20 with the form, and means controlled by the movement of the form for varying the movement of the work-engaging means.
83. In a legging-forming machine, a leg-shaped form about which material may be 25 shaped, means for engaging the material movable toward and from the form, and means for variably determining the extent of approach of the engaging members to the form.
84. In a machine for forming leggings, a 30 form about which sheets of material of different dimensions may be forced to produce leggings of different sizes, means for engaging the material, means for moving the engaging means toward and from the form, and means for determining the extent of approach of the engaging means to the form in accordance with the size of the leggings 35 to be formed.
85. In a forming machine, an elongated 40 form about which material may be shaped, a plurality of members for engaging the material movable toward and from the form, and means common to the plural members 45 and actuated by the machine for variably determining the extent of their approach to the form.
86. In a forming machine, an elongated 50 form varying in contour about its length and about which material may be shaped, a plurality of members for engagement with the material movable toward and from the form, and means actuated by the machine for differently determining the extent of 55 approach of the members to the form at different portions thereof.
87. In a forming machine, an elongated 60 form varying in contour about its length and about which material may be shaped, a plurality of members for engagement with the material movable toward and from the form, and means variable in the operation 65 of the machine for differently determining the extent of approach of the members to the form at different portions thereof.
88. In a forming machine, a form about which material may be shaped, means for engaging the material movable toward and from the form, means for variably determining the extent of approach of the engaging members to the form, and means for locking the determining means in the desired position. 70
89. In a forming machine, a form about which material may be shaped, means for 75 engaging the material movable toward and from the form, means for variably determining the extent of approach of the engaging members to the form, means for locking the determining means in the desired position, and means controlled in the operation 80 of the machine for releasing the locking means.
90. In a forming machine, a form, a form support, work-engaging means movable toward and from the form, and means carried by the form support for controlling the movement of the engaging means with respect to the work. 85
91. In a forming machine, a form, opposite sets of work-engaging members movable toward and from the form, and means movable with each set of work-engaging members for controlling the movement of the 90 said engaging members with respect to the work. 95
92. In a forming machine, a form, a work-engaging member movable toward and from the form, a member having a controlling surface, and a controlling member for the work-engaging member movable with said work-engaging member and contacting with the controlling surface. 100
93. A machine for forming leggings, comprising a leg-shaped form, means for supporting the form to rotate about its longitudinal axis, and means movable toward and from the form for fixing it in position. 105
94. A machine for forming leggings, comprising a leg-shaped form, means for supporting the form to rotate about its longitudinal axis, and movable clamping means 110 contacting with the form.
95. A machine for forming leggings, comprising a leg-shaped form, and relatively movable centers about which the form is 115 movably mounted.
96. A machine for forming leggings, comprising a leg-shaped form, and relatively movable centers about which the form is 120 movably mounted, there being surfaces associated with the centers for contact with the form to fix it in position.
97. In a machine for forming leggings, a leg-shaped form, means for engaging opposite edges of the legging-material to draw it about the form and tension-equalizing means co-operating with the engaging means 125 for opposite sides of the sheet.
98. In a machine for forming leggings, a 130

leg-shaped form, devices arranged in opposite pairs for engagement with the edges of the legging-material to draw it about the form, and tension-equalizing means connecting each pair of engaging devices.

99. In a machine for forming leggings, a leg-shaped form, devices arranged in opposite pairs for engagement with the edges of the legging-material to draw it about the form, tension-equalizing means connecting each pair of engaging devices, and means constructed and arranged to permit the tension applied by the pairs of engaging devices to be varied.

100. In a forming machine, a form, pairs of work-engaging devices co-operating with the form at opposite sides, and yieldable connections between the engaging devices of each pair.

101. In a forming machine, a form, pairs of work-engaging devices co-operating with the form at opposite sides, yieldable connections between the engaging devices of each pair, and means constructed and arranged to vary the yieldability of the connections.

102. In a forming machine, a pair of work-gripping members co-operating with the form at opposite sides, levers upon which the gripping members are supported, and springs interposed between the opposite levers.

103. In a forming machine, a pair of work-gripping members co-operating with the form at opposite sides, levers upon which the gripping members are supported, springs interposed between the opposite levers, and means whereby the effect of the springs may be varied.

104. In a forming machine, a pair of work-gripping members co-operating with the form at opposite sides, levers upon which the gripping members are supported, screws connecting the levers, and springs surrounding the screws.

105. In a machine for forming leggings, a leg-shaped form, and means for separate

engagement with successive portions of legging material along a practically continuous line and through substantially the entire length of opposite edges, and means arranged to move the engaging means toward the form to force the material against said form.

106. In a machine for forming leggings from a sheet of material, a leg-shaped form, material-engaging members movable toward and from the form in a substantially vertical direction, and other material-engaging members movable toward and from the form in a substantially horizontal direction.

107. In a machine for forming leggings from a sheet of material, a leg-shaped form, material-tensioning members movable toward and from the form in a substantially vertical direction, and material-clamping members movable toward and from the form in a substantially horizontal direction.

108. In a machine for forming leggings, a leg-shaped form about which a sheet of material may be held with its opposite sides substantially parallel, opposite series of tensioning members which may be moved in alinement with said opposite sides of the material, and power-operated mechanism for moving the members into engagement with the material.

109. In a machine for forming leggings, a leg-shaped form about which a sheet of material may be held with its opposite sides substantially parallel, opposite series of tensioning members which may be moved in alinement with said opposite sides of the material, power-operated mechanism for moving the members into engagement with the material, and clamping members for the material movable thereafter laterally of the sides.

In testimony whereof we have signed our names to this specification.

WILLIAM E. WADE.
THOMAS H. SEELY.
